CLAIM

The ornamental design for a cushion or similar article, as shown and described.

DESCRIPTION

FIG. 1 is a perspective view of a cushion or similar article incorporating my new design.

FIG. 2 is a top plan view thereof, the bottom being a substantial mirror image of the top.

FIG. 3 is a front elevational view thereof.

FIG. 4 is a rear elevational view thereof.

FIG. 5 is a side elevational view taken from the right of FIG. 3, the side opposite being a mirror image thereof.

FIG. 1.

FIG. 2.

FIG. 3.

FIG. 4.

FIG. 5.
